UNITED STATES PATENT OFFICE.

GEORGE C. JENSEN, OF OAKLAND, CALIFORNIA.

APPARATUS FOR LOCKING LEVERS.

1,262,302.

Specification of Letters Patent. Patented Apr. 9, 1918.

Application filed November 27, 1917. Serial No. 804,263.

To all whom it may concern:

Be it known that I, GEORGE C. JENSEN, a citizen of the United States, residing at Oakland, in the county of Alameda and State of California, have invented certain new and useful Improvements in Apparatus for Locking Levers, of which the following is a specification.

This invention relates to improvements in locks and has for its objects to provide a construction adapted for locking the lever engaging forks of a variable speed power transmitting mechanism from operative movement. The invention consists broadly in the employment of a slidably mounted plate movable with the lever engaging forks and provided with a depression for receiving a plate locking bolt controlled by a suitable locking mechanism.

With the above mentioned and other objects in view, the invention consists in the novel construction and combination of parts hereinafter described.

To more fully comprehend the invention, reference is directed to the accompanying drawings, wherein,

Figure 1, is a vertical sectional view of the preferred embodiment of my invention taken on the line 1—1 of Fig. 2.

Fig. 2 is a broken top plan view, of the construction illustrated in Fig. 1.

Referring more particularly to the several views of the drawings, wherein like characters of reference designate corresponding parts, 1, indicates a suitable casing within the top wall 2 of which is provided parallel spaced operative slots 3, connected by a transverse selective slot 4, the arrangement of the slots providing what is commonly termed an H-slot guide for shift levers. Extending transversely of the casing 1, below and preferably parallel with the selective opening 4, is a suitable shaft 5, rotatably mounted in bearings, and rotatable about and extending upwardly from the same through said slot is a lever 6, normally maintained within said slot by the springs 7, positioned on either side thereof and preferably supported at their lower ends on said shaft.

Positioned one at each side of said lever and one mounted at its lower end to rotate with said shaft 5 and one mounted to rotate about said shaft 5, are the lever engaging forks 8, extending upwardly in said casing

1, and terminating one immediately beneath the respective slots 3, at each side of said selective opening 4, thus it will be apparent that lateral movement of the lever 6, through the slot 4 will cause the same to be received in the upper end of one of said forks 8, and when in such position if operative movement is applied to the lever 6 to move the same longitudinally of the slot 3, the lever engaging fork cooperating therewith is also moved 60 in the direction of movement of the lever.

Slidably mounted within the casing 1, beneath the upper wall 2 thereof are the parallel spaced slide plates 9, slidably longitudinally on the transverse supports 10, and 70 said plates are formed in their adjacent side edges with pockets 11, in which are received the upper ends of the respective lever engaging forks 8, whereby movement by the lever of a lever engaging fork longitudinally of 75 its cooperating slot 3, will cause longitudinal movement of the plate 9, associated therewith.

At a point remote from said pockets 11, the locking slide plates 9 are provided in 80 their adjacent inner edges with semi-circular cut outs or depressions 12, adapted for receiving the locking surfaces 13 of a rotatable slide plate locking bolt 14, projecting downwardly from the underside of a rotatable 85 cup 15 to a point between said plate 9. The slide plate locking bolt is provided on opposite sides with flat faces 16, adapted when the bolt is rotated to aline said faces with the corresponding edges of the locking slide 90 plates 9, to permit free longitudinal movement of said plates through the operation of said lever 6, but on the rotation of said locking bolt 14, to cause the surfaces 13 thereof to seat within the depressions 12, the plates 95 are precluded from longitudinal movement, thereby preventing operative movement of the lever 6, longitudinally of the slots 3. It is desirable to control the rotation of the locking bolt 14 by a suitable lock controlled 100 mechanism, and for purposes of illustration, there is mounted within the cup 15, a locking barrel 17, controlled by any suitable key operating mechanism not illustrated, and within said barrel 17, is a rotating tumbler 105 18, carrying an eccentric surface 19, disposed within a recess 20 in a spring pressed bolt locking pin 21, movable transversely within the cup 15, the outer end of the bolt locking pin 21 being normally maintained within a 110

suitable seat 22, at one side of the cup 15; when the bolt 14, is rotated to locked position, as in Fig. 2 of the drawings, thereby preventing rotation of the cup 15, and the bolt 14, except by the rotation of the tumbler 18, to withdraw the end of the pin 21 from a recess 22, at which time, the cup is free to rotate to remove the surfaces 13, of the bolt 14, depending therefrom, from the depressions 12. The locking of the plates 9 by the bolt 14 is accomplished preferably through the rotation of the cup 15, by the manually controlled handle 23.

Having thus described my invention, what I claim is:

1. In combination with a pivotally mounted lever, a plate provided with parallel slots for guiding the movement of said lever and through which said lever extends, said plate being provided with a slot connecting said parallel slots, a pair of parallel spaced plates, one positioned beneath each parallel slot and formed on their adjacent edges with a seat for permitting lateral movement of the lever into said parallel slots, means for supporting said plates to permit longitudinal sliding movement thereof, and a lock controlled mechanism positioned between said plates for locking the same from movement.
2. In combination with a pivotally mounted lever, a plate provided with parallel slots for guiding the movement of said lever, and through which said lever extends, said plate being provided with a slot connecting said parallel slots, a pair of parallel spaced plates, one positioned beneath each parallel slot and formed on their adjacent edges with a seat for permitting lateral movement of the lever into said parallel slots, means for supporting said plates to permit longitudinal sliding movement thereof, and a lock controlled mechanism positioned between said plates for simultaneously locking the same from movement.
3. In combination with a pivotally mounted lever, a plate provided with parallel slots for guiding the movement of said lever and through which said lever extends, said plate being provided with a slot connecting said parallel slots, a pair of parallel spaced plates, one positioned beneath each parallel slot and formed on their adjacent edges with a seat for receiving said lever when moved into said parallel slots, means for supporting said plates to permit longitudinal sliding movement thereof, and a rotatable lock controlled mechanism carried by said guide plate and extending downwardly therefrom to a point between said plates and capable of operative movement for

simultaneously locking said plates from longitudinal movement.

4. In combination with a pivotally mounted lever, a plate provided with parallel slots for guiding the movement of said lever and through which said lever extends, said plate being provided with a slot connecting said parallel slots, a pair of parallel spaced plates one positioned beneath each parallel slot and each formed on its inner edge with a seat and suitable depressions, said seats adapted for permitting lateral movement of said lever into said parallel slots, means for supporting said plates to permit longitudinal movement thereof, and a lock controlled mechanism for reception within said depressions for locking said plates from longitudinal sliding movement.

5. In combination with a pivotally mounted lever, a plate provided with parallel slots for guiding the movement of said lever and through which said lever extends, said plate being provided with a slot connecting said parallel slots, a pair of parallel spaced plates one positioned beneath each parallel slot and each formed on its inner edge with a seat and suitable depressions, said seats adapted for permitting lateral movement of said lever into said parallel slots, means for supporting said plates to permit longitudinal movement thereof, and a rotatable lock controlled mechanism extending between said plates and capable of operation for reception within said depressions to simultaneously lock said plates from movement.

6. In combination with a pivotally mounted lever, a plate provided with parallel guide slots and through which said lever extends, said plate being further provided with a slot connecting said parallel slots, a pivotally mounted lever engaging fork, positioned beneath each of said parallel slots and with which said lever is capable of selective movement for operating said selective fork longitudinally of its co-operating slot, a pair of parallel spaced plates positioned beneath said guide plate and each adapted to receive one of said forks, and movable longitudinally on the movement of its associated fork, means for slidably supporting said plates and a rotatable lock controlled mechanism for engaging said plates to lock the same from longitudinal movement.

In testimony, whereof I have signed my name to this specification in the presence of two subscribing witnesses.

GEORGE C. JENSEN.
